[57] CLAIM

The ornamental design for a golf putter, as shown and described.

DESCRIPTION

FIG. 1 is a top front perspective view of a golf putter showing my new design;

FIG. 2 is an enlarged fragmentary front elevational view of the putter head;

FIG. 3 is a rear elevational view of FIG. 2;

FIG. 4 is a top plan view of FIG. 2; and

FIG. 5 is a side elevational view of the putter head with the hosel shown in an alternate embodiment of the standard goose-neck form.

The shaft is shown fragmented in FIG. 1 for ease of illustration.

FIG. 2

FIG. 3

FIG. 4

FIG. 1

FIG. 5
